US00D610087S

(12) **United States Design Patent**
Johnson

(10) **Patent No.:** US D610,087 S
(45) **Date of Patent:** ** Feb. 16, 2010

(54) **DRY-TYPE POWER DISTRIBUTION
TRANSFORMER**

(75) Inventor: **Charles W. Johnson**, Wytheville, VA
(US)

(73) Assignee: **ABB Technology AG**, Zurich (CH)

(**) Term: **14 Years**

(21) Appl. No.: **29/341,170**

(22) Filed: **Jul. 31, 2009**

(51) **LOC (9) Cl.** 13-02

(52) **U.S. Cl.** D13/110

(58) **Field of Classification Search** D13/110,
D13/101, 117, 120, 123, 184, 199; 174/DIG. 9,
174/DIG. 25; 242/434, 434.7; 336/60, 83,

(57) **CLAIM**

The ornamental design for a dry-type power distribution transformer, as shown and described.

DESCRIPTION

FIG. 1 is a front and right side perspective view of a dry-type power distribution transformer showing our new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof; and,

FIG. 7 is a bottom plan view thereof.
